GAYLORD W. BEEBE, OF ALBANY, GEORGIA.

CHECK PROTECTOR.

Application filed May 27, 1918, Serial No. 236,774. Renewed September 5, 1924.

The object of my invention is to provide a machine for printing on a check, draft or other instrument through the operation of a key-board wherein all the keys are plainly visible and are operated in a manner corresponding substantially to the keys of a typewriter.

A further object is to provide a machine for marking a check, draft or other instrument on both sides of the paper, in such a way as to do away with the necessity of serating the paper and at the same time give better protection to the check or other instrument and leave it in a neater, stronger, and more perfect condition.

A further object is to accomplish the entire operation of feeding, spacing, locking in position, and marking or printing the check or instrument automatically, by the simple means of one operation, of one key on a key-board for each word or figure to be marked on the check or instrument.

A further object is to provide a machine which will accommodate almost any size check, draft, or other instrument and be easy and convenient to operate.

A further object is to provide a check protector of simple, compact construction and one in which the mechanism is easily accessible for cleansing or repairs.

Other objects of the invention will appear from the following detailed description.

The invention consists generally in various constructions and combinations, all as hereinafter described and particularly pointed out in the claims.

In the accompanying drawings forming part of this specification,

Figure 1 is a plan view of a check protector, being partially broken away,

Figure 2 is a vertical sectional view of the same, taken on the line 2-2 of Figure 3,

Figure 3 is a cross sectional view taken on the line 3-3 of Figure 2,

Figure 4 is a similar view taken on the line 4-4 of Figure 2,

Figure 5 is a cross sectional view, taken on the line 5-5 of Figure 2,

Figure 6 is a cross sectional view taken on the line 6-6 of Figure 2,

Figures 7 and 8 are detail views for marking on the end face of a check,

Figure 9 is a plan sectional view, taken on the line 9-9 of Figure 4.

In the drawing, 2 represents a suitable base on which the operating mechanism of the machine is mounted, and 3 a suitable casing secured to the base at 4. A narrow gap or opening 5 is provided between the base and the walls of the casing for the insertion of the check to be printed or marked. A shaft 6 is journaled horizontally in said casing (see Figure 2) and a suitable type wheel 7 is centrally secured thereon and provided with a series of peripherally arranged characters 8, the impression of which is to be made upon the surface of the check, draft, or other instrument. These characters or figures extend only partially around the peripheral surface of the wheel and the wheel is mounted to turn one-half of a revolution or any desired fraction thereof, as will hereinafter more clearly appear from the detailed description of the operating mechanism.

In the rear of the casing a shaft 9 is horizontally mounted, supporting a series of keys 10 which project through slots 11 in the front of the casing and are provided with suitable caps 12 on which figures or characters or words are printed corresponding to those on the type wheel (see Figure 1).

Loosely mounted in the walls of the casing are shafts 13 and 14, preferably arranged end to end and having freedom of independent oscillation in their bearings.

On these shafts a series of cams 15 are secured, corresponding in number to the keys and in the same vertical plane respectively of the keys to be actuated by the depression thereof. The faces 16 of these cams are concaved on an arc, described from the center of the shaft 9, and the keys have convex surfaces 17 to engage the concave faces of the cams. The cams are arranged so that their faces will be in the form of a spiral, starting from the center in opposite directions, with each cam set at a sufficient distance in the rear of the adjoining one to correspond to the distance between the characters on the wheel 7, the first cam from the outer line (see Figure 4) in either direction being revolved sufficiently by the depression of its key to adjust the first character 8 on the wheel 7 to a position on the underside of the wheel for contact with the upper face of the check and the extreme right and left hand cams being revolved a quarter of a

revolution. When a key is depressed to the limit of its down stroke, its face 17 will seat snugly against the face 16 of its cam and the cam and printing wheel will thereby be locked against movement in either direction until the key is released, and downward movement of each key will be arrested when its surface 19 contacts with the top of the cam. When a key is released, its spring 20 raises it to its normal position.

Secured to the shaft 13 is a gear segment 21 engaging an idle gear 22 that meshes with a gear 23 secured to one end of the shaft 6. The ratio of the segment and gear is two to one. When the key at the extreme left hand end of the keyboard is operated to rotate the cam, the shaft 13 will be revolved a quarter of a revolution and through the gearing above described, the type-wheel will be revolved one-half of a revolution toward the right, bringing the uppermost character or word to a position on the underside of the wheel opposite and adjacent the face of the check to be printed. The other cams on this shaft 13 will travel a proportionately less distance through the operation of their keys and rotate the printing wheel a correspondingly less distance to present the desired character thereon to its printing position. The shaft 14 with its cams is a duplicate of the shaft 13 and its cams, the only difference being in the transmission mechanism, which consists in the gear segment 24 engaging the gear 25 on the same shaft that the printing wheel is mounted on, thereby causing the said wheel to be revolved in the opposite direction from that secured through the operation of the idle gear 22. The movement of the printing wheel through the gear 25 will revolve said wheel toward the left in Figure 4, thereby bringing the upper character or word on the wheel indicated on the key at the extreme right hand of the keyboard in printing position on the underside of the wheel. It will be understood that the shafts 13 and 14, while in concentric relation, are capable of independent operation, each controlled by an independent group of keys and the keys actuating their respective cams on the shafts 13 and 14 for imparting a rotary movement to the type wheel. The purpose of having these two sets of cams and keys is to avoid extreme rotation of the printing wheel in one direction to bring its characters in proper printing position. By operating the wheel first in one direction and then in the other, I am able to reduce its travel and at the same time present quickly each character to its proper printing position.

For the purpose of returning the type wheel 7, the shafts 13 and 14 and their cams to their normal position, I provide pins 26 mounted in the segments 21 and 24. These

pins are engaged by arms 27 secured to the shaft 9 and connected with one another by a rod 28. Springs 29 connect the arms 27 with the casing for raising and holding said arms against stops 30 mounted in the end walls of the casing.

The rod 28 is positioned directly beneath the normal position of the inner ends of the keys 10 and whenever any one of the keys is depressed it will immediately contact with said rod and rock the shaft 9 with its arms 27 and thereby move said arms out of engagement with the pins 26. Further movement of the key will engage its cam, revolve the shaft 13 and set the printing wheel 80 in its printing position, the pin 26 on the segment operated on will follow the arm 27 while the pin and the other segment will travel in the opposite direction. When the key is released, its spring 29 will return the arms 27 to their normal position. One of said arms will contact with the pin 26 in the segment that has been operated and rotate it to its normal position, while the pin 26 in the opposite segment will move in the opposite direction until it contacts with the other arm 27. In this position, the arms 27 will be in contact with the stop pins 30, as shown in Figures 4 and 5.

The convex faces of the keys interlocking with the concave face of the cams 15 and freely moving up or down while in lock, provides a positioning and locking means for the type wheel, while the printing is being accomplished, but as an additional safeguard, I may provide a supplementary locking mechanism as follows: A disc 31 is secured to the gear 25 on the shaft 6. Said disc has a series of peripheral notches 32 corresponding in number to the characters 105 on the wheel 7 in position to be engaged by a tooth 33 on an arm 34 pivoted at 34' on the wheel of the casing and held out of engagement normally with the disc by a spring 35 and a stop pin 36. The arm is 110 provided with an adjusting screw 37 to be engaged by the hub of the arm 27 when it is depressed. This, however, does not occur until the proper character on the printing wheel is in position for printing and 115 when this adjustment has been obtained, one of the slots 32 in the disc will be positioned to receive the tooth 33 for locking the disc and the printing wheel against rotary movement in either direction, while the printing 120 operation is being performed.

It will be noted from an examination of Figure 6 that the downward stroke of the keys is more than necessary for the operation of the cams 15 and that the key moves in the arc of its cam circle some distance after the cams 15 stop rotating. This additional movement is utilized for completing the movement of the check up against the type character on the wheel and also for 130

effecting the supplementary locking mechanism. The mechanism which I prefer to employ for the former purpose I will not describe in detail.

Secured on the shaft 9 are arms 38 connected with one another by a rod 39. Links 40 connect said arms with a yoke 41 pivoted at 42 in the base. A pressure roller or platen 42' is mounted in said yoke and has peripheral projections 43 thereon (see Figures 4, 7 and 8) which contact with the underside of the check and raise it sufficiently to engage the character on the wheel 7 and reproduce such characters or words on the 15 face of the check. The contacting of the pressure roller 42' is arranged to occur when the crank arm 38 is substantially at or near dead center with respect to the link 40 and yoke 41. At such time, the leverage is 20 greatest and the yoke is practically stationary for a considerable arc of the movement. An adjustable screw 44 engaging the rod 39 forms a stop for the arm 38 and prevents overthrow beyond the center. A suitable 25 opening 45 is provided in the base and a similar opening 46 in the plate 47 registers with the opening 45 and through these openings the roller 42' operates. To further protect the check, I prefer to print a 30 continuous line of ink on the underside of the check or instrument, opposite or adjacent the imprint on the face of the check or instrument. To this end the roller 42' and peripheral projection are of a length to 35 fully cover the longest word printed and its space. Inking rolls 48 and 49 are yielding- 40 ly mounted in a carrier or cage 50, slidably mounted at 51 in the base and locked therein by any suitable means, such as an arm 51' 45 on a knob 52 engaging a slot 53 in the base. The carrier can thus be easily removed whenever it is desired to apply ink to the roller 49.

For the purpose of advancing a freshly 45 inked surface 43 of the platen 42' for contact with the underside of the check, I secure a bracket 54 to the base having a pawl to engage the teeth of a ratchet 56 that is secured to the shaft of the roll 42'. Upward movement of the yoke will thereby cause the roll or platen to revolve in contact with the ink roll 48 and for each printing operation a freshly inked projection 43 will be moved into position to contact with 50 the underside of the check, draft or other instrument. A spring 56' engages the notches 57 for holding the ratchet from rotating as the pawl passes from one tooth to another (see Figures 7 and 8).

For the purpose of applying ink to the characters of the type wheel, I prefer to provide carriers or cages 58 and 59 having ink rollers 60 and 61 yieldingly mounted therein. These carriers may be removed 55 from the machine when it is desired to ap-

ply fresh ink to the rollers. For this purpose, the carrier 58 has sliding connections at 60' with the casing 3 and is secured thereto, preferably in the same manner as the carrier 50. The carrier 59 is provided with 70 a projection 61' in its front and a slot 62 to straddle the screw 63. By loosening this screw, the carrier may be readily removed from the machine that the characters on the printing wheel will contact therewith and be 75 inked with each printing operation.

For feeding the check, draft or other instrument to be printed or marked with each successive operation of the printing wheel, I prefer to provide the following described 80 mechanism: A plate 64 is secured to one end of the case and is provided with adjustable guides 65 and 66 for checks or drafts of different widths and lengths, (see Figures 1 and 2) the position of the instrument in 85 the machine being indicated by dotted lines in Figure 1. The end of the check or draft is inserted between feed rolls 66' and 67, the latter being mounted in a yoke 68 carried by a shaft 69 having suitable bearings in the base of the machine and provided with a suitable lever 70 within convenient reach of the operator by means of which the yoke 68 is rocked to depress the roll 67' and allow the insertion of the check or draft between it 90 and the roll 66'. A spring 71 normally holds the roll 67 in contact with the roll 66' with a yielding pressure. The feed roll 66' is secured to the shaft 71' and a similar shaft 72 has bearings in the casing 3. Secured on the shaft 72 is a ratchet wheel 73. An arm 74 is loosely mounted on the shaft 72 on one side of the ratchet wheel, held in place by a collar 75 on said shaft. On the other side of the ratchet between it and a collar 76 I mount a bracket 77. The shafts 71 and 72 have gears 78 and 78' in mesh. The arm 74 has an extension provided with a pawl 79 held in engagement with the teeth of the ratchet 73 when in its normal position by means of a stop 80 (see Figure 2) and thereby the ratchet is prevented from moving too far. A spring plate 81 prevents backward movement of the ratchet. The arm 74 has a pivotal connection at 82 with 100 a link 83 which is pivoted at 84 on a yoke 85 which has arms 86 loosely mounted on the shaft 9. Said yoke is normally held in its raised position by means of springs 87 attached to the arms 86 and its movement is limited by the pawl 79, the ratchet teeth and the stop 80. Assuming that the word "one" is being printed, the pawl will move over four teeth of the ratchet and upon return of the key and the type wheel the check 105 will be advanced four spaces, one for each of the letters in the word "one" and one for a space between the word and the next character to be printed. The pawl 79 will move back as many teeth on the ratchet as there 110

are letters in the word to be printed plus one for the space.

To accomplish this result, I provide the yoke with a series of steps 88 cut to varying depths according to the required travel of the yoke for the key opposite which the step is located. In printing a long word, or one containing a number of letters, the key will have a shorter travel before coming in contact with its step on the yoke as when printing a short word and as movement of the yoke will begin upon contact of the key therewith, it is evident that with the printing of a long word, and the travel of the key being always the same, the yoke will be rocked further than in printing a short word. The pawl will therefore move farther in printing a long word and travel over a greater number of teeth on the ratchet than in printing a short word and through the gears 78 and 78' operate the feed wheels 66' and advance the check or draft a corresponding distance. The travel, therefore, of the check in the machine is commensurate with the movement of the yoke, the keys for the short words through the yoke mechanism described operating the feed wheels of the check a distance corresponding to the length of the word and increasing as the length of the words to be printed increases, the height of the step in each case controlling the feed of the check or draft. The keys may have figures thereon or words, as may be desired, each key having a word or character thereon corresponding to the one on the printing wheel which is adjusted in its printing position through the mechanism described by the operation of its key, and is thereafter locked in this position while the printing is being done by the convex and concave faces of the key and cam and also by the supplementary locking mechanism heretofore described. This latter may be omitted and various other modifications may be made in the construction without departing from the spirit of the invention.

I claim as my invention:

1. A check protector comprising a printing wheel having a series of peripheral marks or characters and mounted to be rocked in opposite directions, groups of cams mounted on an axis parallel with the axis of the printing wheel, means connecting one group of cams with the printing wheel to rock it in one direction and connecting the other group with the wheel to rock it in an opposite direction, said cams being positioned to impart different extent of movements to the printing wheel and disposed in the path of movement of operating keys whose axis is parallel with the axis of the cams, and keys for the cams of the different groups, said keys being disposed to be normally out of contact with their cams and adapted to be moved into contact with their cooperat-

ing cams for movement of the printing wheel.

2. A check protector comprising a printing wheel having a series of peripheral marks or characters and mounted to be rocked in opposite directions, groups of cams mounted on an axis parallel with the axis of the printing wheel, means connecting one group of cams with the printing wheel to rock it in one direction and connecting the other group with the wheel to rock it in the opposite direction, said cams being positioned to impart different extent of movements to the printing wheel, keys for the cams of the different groups of cams disposed to make contact with their respective coacting cams to move the printing wheel, means for restoring the cams and printing wheel to normal position on release of the keys, and means coacting with the keys to render ineffective the restoring means when the keys are moved for contact with the cams.

3. A check protector comprising a printing wheel having a series of peripheral marks or characters and mounted to be rocked in opposite directions, groups of cams mounted on an axis parallel with the axis of the printing wheel, means connecting one group of cams with the printing wheel to rock it in one direction and connecting the other group with the wheel to rock it in the opposite direction, said cams being positioned to impart different extent of movements to the printing wheel, keys for the cams of the different groups of cams disposed to make contact with their respective coacting cams to move the printing wheel, a second printing member disposed at the underside of the printing wheel and carried by a rocking arm, a jointed-link connection between the rocking arm and a member positioned in the path of travel of the actuating keys and actuated by the keys for moving the second printing member into cooperative relation to the printing wheel.

4. A check protector comprising a printing wheel having a series of peripheral marks or characters and mounted to be rocked in opposite directions, groups of cams mounted on an axis parallel with the axis of the printing wheel and disposed in the path of movement of operating keys whose axis is parallel with the axis of the cams, means connecting one group of cams with the printing wheel to rock it in one direction and connecting the other group with the wheel to rock it in the opposite direction, keys for the cams of the different groups of cams disposed to make contact with their respective coacting cams to move the printing wheel, means for feeding paper to the printing wheel, said means including a step-shaped member positioned in the path of travel of the operating keys and con-

nected with a progressively moved device for engagement with the paper, the steps of the step-shaped member conforming to a predetermined movement of the keys corresponding to the length of the characters to be printed, the step-shaped member being actuated by the keys which operate the printing wheel.

5. A check protector comprising a printing member having peripheral marks or characters thereon, a set of operating keys, a corresponding number of cams having concave surfaces to receive corresponding convex surfaces provided on said keys, and 10 mechanism connecting said cams with said printing wheel.

6. A check protector comprising a printing wheel having peripheral marks or characters thereon and mounted to rock in opposite directions to present said characters to a printing position, shafts mounted in concentric relation adjacent to said wheel and geared thereto, cams mounted in grooves on said shafts and having contracting surfaces 25 in staggered relation for varying the stroke of said cams and the travel of said printing wheel, and a corresponding number of actuating keys mounted to engage the contacting surfaces of said cams for operating them 30 and said wheel.

7. A check protector comprising a set of operating keys, a rotatable printing member, having marks or characters spaced thereon, a second rotatable printing member having 35 spaced projections thereon, and being movable against the first named printing member, mechanism co-operating with said keys for feeding and spacing a check or other instrument between said printing members, commensurate with the length of 40 the marks or characters to be printed, and mechanism for inking both printing members, and printing said check on opposite sides, all of said devices being cooperatively 45 connected for operation by a single operation of a key.

8. A check protector comprising a set of operating keys, a movable printing member having marks or characters spaced thereon, a second printing member movable against the first named member, said printing members adapted to print on both sides of a check, and mechanism co-operating with the keys for feeding a check or other instrument between said printing members and spacing it commensurate to the length of the character to be printed and means for actuating the two printing members for printing the check or instrument on both sides, 55 all of said operations, including the moving of the printing members, being performed by a single operation of a key.

9. A check protector comprising a set of operating keys having visible marks or characters, a movable printing member having

corresponding marks or characters spaced thereon, a second printing member movable against the first named member, said printing members adapted to print on both sides of a check, and mechanism co-operating with the keys for feeding and spacing a check or other instrument between said two printing members, commensurate with the length of the mark to be printed, and means for locking one of said printing members against movement while the check is being printed on both sides, all of said operations being effected by a single operation of a key.

10. A check protector comprising a movable marking member having marks or characters thereon, a set of operating keys adapted to rock or oscillate around a common center and having visible marks corresponding to the marks on the marking member, a number of cams arranged to be rocked by said keys and having concave surfaces to receive corresponding convex locking surfaces provided on the keys, connections between said cams and said marking member and feed mechanism including a progressively moved device and a step-shaped member connected therewith and positioned in the path of movement of the keys for commensurately feeding paper relatively to the marking number upon actuation of a key.

11. A check protector comprising a rotatable printing member having a series of differentiated printing characters spaced thereon, a series of operating keys, each key having a visible character corresponding to a character on the printing member, a second rotatable printing member having a series of printing surfaces and being movable against the first named member, mechanism operative by the movement of the keys for feeding and positioning a check or other instrument between the printing members for each stroke of a key and commensurate to the length of the character to be printed plus a space, mechanism also operative by the keys for supplying ink to both printing members and printing differentiated characters on one side of the check or instrument and a longitudinal mark with respect to the check on the other side of the check opposite the imprint on the face of the check or instrument.

12. A check protector comprising a movable printing member having a series of marks or characters spaced thereon, a set of operating keys having corresponding visible marks or characters, a second printing member, being movable against the first named member and having a printing surface, mechanism operative by the movement of a key for feeding and positioning a check or other instrument between said printing members and applying printing ink to both

of said members, and mechanism co-operating with the key and printing members for printing the mark or character visible on the key on one side of the check or instrument 5 and a mark with respect to the check on the other side by the last movement of the key.

13. A check protector comprising a rotatable printing wheel having differentiated marks or characters spaced thereon, a series 10 of operating oscillating keys having visible marks or characters corresponding to the marks on the printing wheel, a second printing wheel or platen having a longitudinal uniform printing surface, a series of cams 15 arranged in the path of said keys and having concave surfaces to be engaged and rocked by the keys and receive corresponding convex locking surfaces provided on the keys, connections between said cams and said 20 printing wheel, mechanism for feeding a check or other instrument between the first printing wheel and second printing wheel a distance commensurate to the length of the character to be printed, and inking devices 25 for supplying ink to both printing wheels, all of said parts being cooperatively connected to act in conjunction in one operation of each key.

14. A check protector comprising a set of 30 operating keys, having visible marks or characters, a primary rotatable printing member having corresponding marks or characters circumferentially spaced thereon, a secondary printing member and platen 35 movable against the primary member, mechanism including cams operating when a key is struck for moving the primary printing member into position to bring its mark, corresponding to the mark on the operated 40 key, into alignment with the secondary printing member, mechanism including a yoke for feeding a check or other instrument between said printing members and spacing it commensurate with the 45 length of the mark on the operated key, mechanism co-operating with the key for locking the primary printing member

against movement when the check is in position, and mechanism for operating the platen in printing, all of said mechanism, including means for restoring all the parts, being cooperatively connected to complete a full cycle of movements by one forward and one backward stroke of a key.

15. A check protector comprising a wheel 55 mounted to rock on a longitudinal axis and having a series of peripheral marks or characters thereon, a set of operating keys and mechanism actuated by the movement of said keys for rocking said printing wheel to adjust a character thereon in a printing position, a check or draft feeding means, a rocking yoke having a series of steps therein in the path of said keys, and actuated by said keys, the depths of said steps being commensurate respectively with the lengths of the marks on the printing wheel, and mechanism connecting said yoke with said check feeding means and including a ratchet wheel fixed to a transmitting shaft and an arm loosely 70 mounted on the same shaft and carrying a pawl coacting with the ratchet wheel and actuated from said yoke.

16. A check protector comprising a printing wheel mounted to rock on a longitudinal 75 axis and having a series of peripheral marks or characters thereon, a set of operating keys and mechanism actuated by the movement of said keys for rocking said printing wheel to adjust a character thereon in a printing 80 position, a check or draft feeding mechanism, a rocking yoke member having a series of steps therein of different height in the path of said keys, and actuated by said keys, the height of said steps being commensurate 85 with the required stroke of travel of said yoke, and a link having a pivotal connection with said yoke member and connected with the check moving mechanism through a pawl and ratchet actuated from the yoke. 90

In witness whereof, I have hereunto set my hand this 14th day of May, 1918.

GAYLORD W. BEEBE.
